TYPE ACTION SYSTEM FOR PORTABLE
TYPEWRITERS

Joseph Louis Adhémar Borel, Paris, France, assignor to Societe "Rooy," a French joint-stock company

Application July 25, 1945, Serial No. 606,906
In France June 10, 1944Section 1, Public Law 690, August 8, 1946
Patent expires June 10, 1964

1 Claim. (Cl. 197—27)

1

My invention has for its object a typewriter of the so-called portable type.

Obviously, if a typewriter is to be ranked in this class, it must first have the least possible bulk, above all in height, in order to facilitate its handling and carrying.

A rather great number of so-called portable typewriters have been put on the market which, in spite of the substantial difference existing between their height and those of the so-called office typewriters, are nevertheless still much too high and cumbersome to allow their practical carrying by the user.

The following description and accompanying drawings given out by way of a non-limitative example will allow a proper understanding of the manner of executing my invention. In said drawings:

Fig. 1 is a vertical cross-section of the typewriter.

Figs. 2, 3 and 4 are fragmentary sectional views allowing a comparison between the type bars according to my invention and the similar arrangement in common use.

Up to the present, for the purpose of decreasing the height of the known portable typewriters, it had been deemed sufficient to crowd together the main elements that exist in every office typewriter without incorporating thereto those important modifications which are indispensable for the production of very low typewriters. According to my invention, the height can be cut down to even less than forty millimeters, and for that purpose the entire device comprises arrangements whereby, as will be described later on, two capital objections to usual portable typewriters can be avoided, viz:

(a) the original height of the whole typing system: said height will be cut down as a result of a widening to the utmost of the angle of action of the type bars;

(b) the height of the types above the base of the typewriter, which height generally tends to increase from the central bar towards either end bar; a considerable reduction in such height will be secured by the provision of two different kinds of type bars.

In the drawings, 1 and 11 designate two of the type bars one of which is in operative position with reference to the cylinder or platen 14 while the other is in its position of rest in contact with the cushion 9.

2 designates the sector carrying a curved rod 3 to which the type bars are fulcrumed.

A wire link 4 connects the type bar 1 with an

2

intermediary lever 5 while a further wire link connects the bar 11 with the intermediary lever 51. These intermediary levers 5—51 are pivotally secured to a curved rod 6 mounted on a support 6.

Links 7 and 71 connect the intermediate levers with the key levers 8 and 81.

9 and 11 designate typing keys and 12 the support for key levers 8; 13 is the fulcrum rod for the key levers and 17 the type bar return spring.

Since all the type bars are actuated similarly it will be assumed in the following, in order to simplify the description, that the bar 1 provided with its actuating gear is nothing else than bar 11; likewise provided with its actuating gear, transferred from its inoperative position on cushion 9 into its operative position on platen 14 (Fig. 1).

If now the key 11 on key lever 8 occupying 20 then the position shown (in dash-and-dot lines in Fig. 1) be depressed for the purpose of printing a sign, said lever will be caused to rock on rod 13 and to assume the position shown in full lines in Fig. 1.

25 During the said movement of lever 8 the arm 82 of said lever has pushed towards the left the link 7 which, being fulcrumed on the intermediate lever 5 pivoted on 6, has thrown said lever from its position 51 into its position 5, this 30 causing through link 4 the actuation of bar 1 which, being fulcrumed on rod 3, is swung from its inoperative position 11 into its operative position 1 on platen 14.

It will be seen on Fig. 1 that the point of 35 articulation of link 4 on lever 5 has described the arc 15 and that the point of articulation of link 4 on the type bar 1 has described the arc 16. Such an arrangement thus enables the point of articulation of link 4 on type bar 1 to describe 40 about the fulcrum rod 3 an arc which is kinematically available on a very wide angle, e. g. 180° and even more, this resulting, as shown in Fig. 1 in a considerable flattening of the type bar basket, this result being obtained without any gear work.

45 In addition, as shown in the drawings and as a result of the particular arrangement that will be described later on, the special shapes of the type bars 1, intermediate levers 5 and key levers 8 enable the same to be lodged and to move in a very low space (Fig. 1).

In this printing device the fulcrum rods 3 and 51 carried by the sector 2 and the support for the intermediary levers 6 are curved on arcs 53 concentric with the bend point of the type bars.

and located in parallel planes at an angle with respect to the base of the typewriter; the support for the key levers 12 is straight and arranged at right angles to the longitudinal axis of the typewriter.

With the printing device described a type basket is obtained that is very shallow in its middle portion, i. e. on the central bars 11 shown in Figs. 1 and 2, whereas if the sector 2 were fitted all over with bars similar to 1, 11, the side bars would come to rest on the circular support 6 of the intermediate levers and could not fall back on the cushion 9 as shown at B in Fig. 3. The whole height-saving would thus be lost unless this difficulty were overcome as follows:

The explanation will be given with reference to the end bar which in the present instance corresponds to the furthest position of type 12 above cushion 9.

The end type bar in Figs. 3 and 4 is designated by 13 or 14.

When considering Fig. 3 it will be found that the bar 13 as it swings back towards the keyboard comes into engagement with the support 6 at point 18.

By transferring said point 18 to Figs. 3 and 4 the position is obtained which is shown in Fig. 3 where said bar is supposed to be identical to bar 11 in Fig. 2; the height of the typewriter as represented by the arrow 20 (Figs. 2 to 4) would thus be increased by the height 19, which would amount to height 21. Of course, such heights are given only as indications. In order to decrease the overall size the type 12 must be brought down to the level of cushion 9. For that purpose a special shape shown at 14 (Fig. 4) is given to the type bar.

It is apparent that bar 14 is shaped to fit the outline of the support 6 and that the type carried by said bar can rest on cushion 9.

Consequently, the typewriter is provided with two kinds of type bars, viz.: central bars 11 (Figs. 1 and 2) and end bars 14 (Fig. 4).

24 in Figs. 2 to 4 locates vertically the fulcrum rod 3 of the central type bar 11, 25 indicates the height of the side portions of rod 3 with respect to the middle portion 24, and 26 indicates the position of the support 6 with respect to 25.

The above described arrangements are mentioned by way of example only, since the shapes, sizes and details of construction and application can be modified without departing from the

characteristics of this invention as defined in the accompanying claim.

What I claim as my invention and desire to secure by Letters Patent is:

5 A portable typewriter comprising key levers, a horizontal straight fulcrum rod having the said key levers pivoted thereon, type bars, a fulcrum rod curved in a sloping plane and having the type bars pivoted thereon, an intermediate curved fulcrum rod between the aforesaid ones, intermediate levers pivoted on said intermediate fulcrum rod, fixed supports on which the three fulcrum rods are mounted, wire connections between the intermediate levers and said key levers and type bars, the intermediate fulcrum rod and its support having their ends at a higher level than their middle portions, a horizontal curved cushion serving to support the type bars in their rear-most positions, said type bars being of two different kinds, those in the side portions being offset downwardly at the rear of the intermediate lever support to compensate for the difference in the levels of their fulcrums and those of the bars in the middle portion in such manner that 10 the horizontal cushion on which the free ends of all bars come to rest can be located at a short vertical distance above the intermediate lever fulcrum rod.
